UNITED STATES PATENT OFFICE.

NATHANIEL W. LILLIE, OF SOMERVILLE, AND ANTON FREIER, OF BOSTON,
MASSACHUSETTS, ASSIGNORS TO HOLTZER CABOT ELECTRIC COMPANY,
OF BROOKLINE, MASSACHUSETTS, A CORPORATION OF MASSACHU-
SETTS.

WIRE-CONNECTOR.

No. 806,477.

Specification of Letters Patent.

Patented Dec. 5, 1905.

Application filed February 20, 1905. Serial No. 246,428.

To all whom it may concern:

Be it known that we, NATHANIEL W. LILLIE, residing in Somerville, county of Middlesex, and ANTON FREIER, residing in Boston, county of Suffolk, State of Massachusetts, citizens of the United States, have invented an Improvement in Wire-Connectors, of which the following description, in connection with the accompanying drawings, is a specification, like letters on the drawings representing like parts.

The present invention relates to a wire-connector for connecting one wire with another in electrical contact, the purpose being to obtain a connector which can be used for connecting together the ends of two wires running in the same direction or, if necessary, connecting a branch wire to a main wire without cutting the said main wire.

The connector embodying the invention consists of a member formed of conducting material adapted to envelop the connected wires and to bring them into intimate electrical contact throughout the length of the joint, the tensile strength being obtained by twisting the wires with the connector applied thereto.

The connector embodying the invention consists of a strip of conducting metal of a pliable nature and of good electrical conductivity, such as copper, the edges of the said strip being bent around toward each other, so as to form two parallel recesses to receive the ends of the wires which are to be connected. The edges may be bent until they come nearly into contact with the base of the strip to form a tube, or in some cases one or both edges may be bent over only far enough to form a channel to receive the wire, which can then be inserted lengthwise instead of endwise. In the latter construction it is desirable to make a sharp bend just back of the edge of the strip, so that the said edge will lie in close contact with the wire and be drawn into close engagement therewith during the twisting process.

A further feature of the invention consists in making the middle of the connector softer and more pliable than the ends by drawing the temper of the strip in the middle portions and leaving the ends comparatively hard.

Figure 1 is a perspective view of a wire-

joint embodying the invention in which both recesses are substantially closed. Fig. 2 is 55 an end view of the same on an enlarged scale. Fig. 3 is an enlarged end view of a connector, showing a slight modification. Figs. 4 and 5 show, respectively, a perspective view and an enlarged end view of a connector with a further modification. Fig. 6 is a plan view of two wires connected, and Fig. 7 is an enlarged transverse section taken through the middle of Fig. 6.

As shown in Figs. 1 and 2, the connector 65 is formed of a strip of sheet metal, preferably copper, the ends of which are rolled over toward each other and toward the body of the strip, so as to form two parallel recesses *a*, which may be made slightly larger in diameter than the wires to be connected, so that the said wires can be readily inserted endwise. The wires when the ends thereof have been inserted in the recesses are securely connected together by twisting the ends of 70 the connector with the wires therein in opposite directions, so that the two wires are twisted together, as shown in Fig. 6. In the twisting operation the adjacent edges of the connecting-strip are not only forced close 75 together, but also snugly into contact with the surface of the wire, so that they come into perfect electrical contact therewith over the entire surface, as shown in Fig. 7.

In Fig. 7 the outlines of the wires and of 85 the surfaces of the connector where these parts are in contact are indicated by fine lines, the contact, however, being so perfect in the actual article that when the wires are cut through the middle of the connector 90 these lines are only faintly visible.

As indicated in Fig. 3, that portion of the connecting-strip which lies between the two adjacent recesses may be bent upward slightly, so that the recesses conform a little 95 more closely to the wires. This construction, however, is not essential, since the wires can be perfectly connected when the back of the strip is left substantially flat.

In cases where a branch wire is to be connected with an unbroken main wire so that it is impossible to insert the latter endwise in the recesses the connector may be shaped as shown in Figs. 4 and 5, one edge of the strip being at a sufficient distance from the other 105 rolled-over edge to admit the lateral inser-

tion of the unbroken wire. In this case we prefer to bend the said edge at a more or less abrupt angle, as indicated at α^2 , so that after the wire has been inserted the connector can 5 be closed thereon by means of pliers, the bent-in edge hugging closely the surface of the wire and being drawn still closer into contact therewith when the wires are twisted.

A further important feature of novelty 10 consists in the varying degrees of hardness in different parts of the connector, the part between the ends being much softer and more pliable than the parts adjacent to the ends. This quality is obtained in tempering 15 the connector and is important for the reason that the connector thus made, while stiff enough at the ends to get a hold on the wire, is so soft in the middle as to be drawn into perfect electrical contact with the wire, 20 there being no particular strength needed in this part of the connector, since the wires are held together through the twisting of the two.

We claim—

1. A wire-joint consisting of a metallic strip, the edges of which are bent over toward each other, and toward the body of the strip, one of the said edges being close to the body of the strip, and the other edge being separated from the body of the strip by a space sufficient to admit a wire laterally, the 25 said latter edge being also bent at an angle, substantially as described.

2. A wire-connector comprising a strip of metal shaped to form adjacent recesses to receive the wires, the said metal being softer 30 and more pliable in the middle than at the ends.

In testimony whereof we have signed our names to this specification in the presence of two subscribing witnesses.

NATHANIEL W. LILLIE.
ANTON FREIER.
